UNITED STATES PATENT OFFICE

135,677

DESIGN FOR A PACKAGE FOR FIRE EXTINGUISHING MATERIAL OR SIMILAR ARTICLE

Harley G. Hastert, Marinette, Wis., assignor to Dugas Engineering Corporation, Marinette, Wis., a corporation of Delaware

Application February 19, 1943, Serial No. 109,581

Term of patent 14 years

To all whom it may concern:

Be it known that Harley G. Hastert, a citizen of the United States, residing at Marinette, Marinette County, in the State of Wisconsin, has invented a new, original, and ornamental Design for a Package for Fire Extinguishing Material or Similar Article, of which the following is a specification, reference being had to the accompanying drawings, forming a part thereof.

Figure 1 is a front perspective view of a package for fire extinguishing material or similar article, showing my new design.

Figure 2 is a front elevational view taken along lines 2—2 of Figure 3.

Figure 3 is a side view taken along lines 3—3 of Figure 1.

Figure 4 is a rear elevational view taken along lines 4—4 of Figure 3, and

Figure 5 is a bottom plan view taken along lines 5—5 of Figure 2.

I claim:

The ornamental design for a package for fire extinguishing material or similar article, as shown.

HARLEY G. HASTERT.
